G. OAKLEY.

DOOR ENGINE CONTROL CIRCUITS,
APPLICATION FILED AUG. 28, 1919.

1,424,257.

Patented Aug. 1, 1922.

George Oakley Inventor
By his Attorney

E. M. Bentley

UNITED STATES PATENT OFFICE.

GEORGE OAKLEY, OF ALBANY, NEW YORK, ASSIGNOR TO CONSOLIDATED CAR HEATING COMPANY, OF ALBANY, NEW YORK, A CORPORATION OF WEST VIRGINIA.

DOOR-ENGINE CONTROL CIRCUITS.

1,424,257.

Specification of Letters Patent. Patented Aug. 1, 1922.

Application filed August 28, 1919. Serial No. 320,387.

To all whom it may concern:

Be it known that I, GEORGE OAKLEY, a citizen of the United States, residing at Albany, in the county of Albany and State of New York, have invented certain new and useful Improvements in Door-Engine Control Circuits, the following being a full, clear, and exact disclosure of the one form of my invention which I at present deem preferable.

10 For a detailed description of the present form of my invention, reference may be had to the following specification and to the accompanying drawings forming a part thereof.

15 In the control of car-door engines of the pneumatic type, it is well known that electromagnets are frequently employed to operate the proper engine valves for the opening and closing movements of the respective engines. These magnets are usually in circuits which are dominated by push-button switches that the operator presses to either open or close the doors. Such apparatus is so well known as to require no 20 illustration thereof herein, only the circuits, switches, and magnets being shown in the drawings.

25 In such an arrangement it has occurred that after the operator has pressed the door-opening buttons, the engine of one particular door fails to respond by reason of the sticking of the door. This failure remaining unnoticed, the operator subsequently may fail to press the closing button of the defective door, but will press those of all the doors which are open.

30 At the door which failed to open, however, the valve remains set in the open position and the movement of the restarted train may jar the door sufficiently to release it and, as it is set to open, it will so operate and open unexpectedly, while the train is running, probably with disastrous results.

35 It is the purpose of my present invention to prevent an accident of that kind. I accomplish this in an extremely simple way by an interlock circuit containing at each door a switch so arranged that its contacts are closed when the door is closed. This switch connects the closing valve magnet for each door to the said interlock circuit and said circuit is thereby energized when any closing button for any door on the same 40 side of the car is pressed. Thus, in case any

door fails to open as above described, its valve is sure to be thrown to the closed or safe position by the mere pressing of the closing button for any other door. Hence no valve can be left in an open position when 45 it should be in closed position.

The drawing shows the circuits for a car having three doors on each side.

The doors on one side of a car constitute a separate group having its own circuits, 50 and the push-buttons therefor may be located at any convenient position. As shown in the drawing, there are at the left end of the car, at D, two sets of push-buttons dominating the door at the same end, also 55 the center door on one side of the car. At the right end at D² are corresponding buttons dominating the door at that end, also the center door on the same side. On the opposite side of the car, at D¹ and D² are 60 similar push-buttons similarly dominating the doors on that side. Each door has a magnet E which controls the closing action of the door-operating engine for that door, also a magnet F controlling its opening action. For example, when button 1 is pressed, 65 it closes a circuit from B, through opening magnet F at the center door to ground, and when button 2 is pressed it closes a circuit from B through the opening magnet F at 70 the left end door. Similarly the pressing of button 3 closes a circuit from B through the closing magnet E at the center door and the pressing of button 4 closes a similar circuit through closing magnet E at the 75 left end door. The same system is followed at all of the other buttons, and there is no 80 novelty in that arrangement.

K represents a wire forming a supplementary circuit which I term an interlock 85 circuit. At A, A, etc., are switch contacts that are held closed, so long as the doors corresponding thereto respectively are closed. These contacts connect said wire K to the circuit of the corresponding closing 90 magnets E at every door and, if any door fails to open, it will leave the said circuit K so connected. By this means the subsequent pressing of the door-closing button for any individual door will act, through 95 the contacts left closed at A, to energize any of the closing magnets E on the same side of the car which may be improperly in the open position. For example, the pressing of button 3 will not only admit 100

105

110

current from B to magnet E at the center door but also to the magnet E of the left end door and of the opposite end door on the same side of the car, in the event of the 5 wire K being left connected to either of their closing magnets, by the failure of either door to open and break that connection at its contacts A.

If therefore any one of the three doors 10 has failed to open when its opening magnet F has acted to set the valve of its engine to the opening position, the subsequent pressing of button 3, or any one of the other closing buttons 4, 7 and 8 will energize the magnet E at the door which has failed to open, as well as the magnet E at the door or doors 15 normally controlled by the button pressed. Thereby the defective door is not left with its engine valve set to opening position and 20 in danger of being opened after the train has started. This arrangement does not interfere with the individual control of the several doors by their individual opening and closing buttons.

25 What I claim as new and desire to secure by Letters Patent is:

1. In a door operating system the combination with a door of a door closing circuit including a magnet, a switch for initiating 30 the closing action of the door when the latter is open, and a supplemental circuit controlled by the door for energizing the same magnet while the door is closed.

2. In a door operating system the combination with a door including a magnet and 35 a switch for initiating the closing action of a door when the latter is open, and a supplemental circuit including the same magnet and an energizing switch, said last 40 mentioned switch being held in closed position while the door is closed.

3. In a door operating system the combination with a door of a door closing circuit including a magnet and a switch for initiating 45 the closing action of the door when the latter is open, and a supplemental circuit including said magnet and provided with contacts maintained in engagement while the door is in closed position.

50 4. In a door operating system the combination with a plurality of doors of a corresponding number of circuits including magnets and switches for initiating the closing movements of the respective doors when the latter are open, and a common supplemental control circuit including all of the said magnets, and energizing switches for the said control circuit normally maintained in closed position by the respective doors when 55 they are closed.

5. In a door operating system the combination with a plurality of doors and engines therefor of a corresponding number of door closing circuits including magnets and switches for initiating the closing action of 65 the respective door engines, and a supplemental control circuit including the same magnets and containing switches located at each door and controlled by the latter.

6. In a door-operating system the combination with a series of doors of a series of magnets controlling the opening of the doors, a second series of magnets controlling the closing of the doors, individual switches for each of the opening magnets, 75 individual switches for each of the closing magnets, and an interlock circuit by which each of the closing-magnet switches can operate all of the closing magnets.

7. In a door-operating system, the combination with a series of doors, of an engine for closing each of the doors individually, magnets controlling the opening action and the closing action separately for the respective doors, an individual switch for each 85 magnet and an interlock circuit by which each of the closing switches can energize all of the closing magnets.

8. In a door-operating system, the combination with a series of doors of two sets of 90 magnets, one set controlling the opening and the other set controlling the closing of the respective doors, individual switches for the several magnets, and an interlock circuit controlled by each of the door-closing 95 switches and including all of the door-closing magnets.

9. In a door-closing system the combination with a series of doors and their respective operating devices, of two sets of magnets, one controlling the closing and the other the opening action of said devices, individual switches for each of the several magnets and an interlock circuit containing circuit-closers controlled by the position of 100 the doors and dominated by each of the closing switches.

10. In a door-closing system for cars the combination with a group of doors on the same side of a car, of a series of magnets controlling the opening and closing of the doors and switches for said magnets, and a locking circuit dominated by the door-closing switches and serving to energize all of the door-closing magnets.

Signed at Albany, county of Albany and State of New York, this 22nd day of August, 1919.

GEORGE OAKLEY.
